CLAIM

The ornamental design for clip on monocles, as shown and described.

DESCRIPTION

FIG. 1 is a side perspective view of my new design for clip on monocles;

FIG. 2 is a front elevation view of my new invention;

FIG. 3 is a rear elevation view of my new invention;

FIG. 4 is a left side elevation view of my new invention;

FIG. 5 is a right side elevation view of my new invention;

FIG. 6 is a top plan view of my new invention; and,

FIG. 7 is a bottom plan view of my new invention.

The broken lines indicating the logo are for the purposes of illustrating a possible logo and form no part of the claimed design.
